UNITED STATES PATENT OFFICE.

ROBERT A. BACHMAN, OF EAST ORANGE, NEW JERSEY, ASSIGNOR, BY MESNE ASSIGNMENTS, TO INDUSTRIAL Poured CONCRETE HOUSE CO., A CORPORATION OF NEW JERSEY.

CONCRETE-HOUSE MOLD.

1,271,262.

Specification of Letters Patent.

Patented July 2, 1918

Application filed August 2, 1916. Serial No. 112,726.

To all whom it may concern:

Be it known that I, ROBERT A. BACHMAN, a citizen of the United States, residing at East Orange, in the county of Essex and State of New Jersey, have invented certain new and useful Improvements in Concrete-House Molds, of which the following is a full, clear, and exact description.

This invention relates to molds for the construction of small concrete houses such as are erected by industrial corporations for their employees.

One object of the invention is to provide a mold, for casting the entire house including the walls and floors of the several stories at a single pour, of such a construction, that the floors as well as the walls, may be cast uniformly and of a proper thickness.

Another object of the invention is to provide a mold which may be completely assembled to cast the entire building and thereafter be taken apart with the greatest ease and rapidity.

A further object of the invention is the provision of simple but adequate means for supporting the mold rigidly in position while the concrete is being poured, which supporting means is of sufficient strength to withstand the stresses and strains of the heavy mass of concrete utilized in casting the entire building at a single operation.

A still further object of the invention is to provide a mold in which window and door openings may be formed simultaneously with the casting of the walls and floors, which window and door openings may be positioned at any desired location in the building.

To attain these objects, the invention consists in a mold consisting of an outer and an inner mold form; the outer mold form is a hollow rectangular structure of sufficient height to form the several stories of the building, while the inner mold form consists of a plurality of box-like structures having closed tops and open bottoms, which are superimposed and spaced one above the other a distance equal to the thickness of the concrete floor to be cast. These box-like structures are also spaced from the outer mold form a distance corresponding to the thickness of the walls to be cast, and in this

manner when the mold is completely assembled, the spaces which are to be filled with concrete to form the walls and floors are in open communication with each other, permitting a monolithic structure to be obtained. Moreover, since the box-like structures of the upper stories have open bottoms and the concrete which forms the floor is sustained only by the closed top of the box-like structure below, access is permitted to the mass of concrete which is to form the floor to permit it to be properly distributed and thus a uniform floor of even thickness obtained.

Where the house is to have more than one room upon each story, a plurality of such box-like structures may be utilized for each story and by spacing them from each other the proper distance a partition wall may then be cast simultaneously with the walls and the floor.

In the specific embodiment of the invention disclosed metallic mold plates having marginal flanges are preferably used in the construction of both the inner and outer mold forms, which plates are preferably made long and relatively narrow and are vertically disposed to form the side walls of both the inner and outer forms, the plates of each form being of such a length as to substantially cast the walls for one story of the building. Instead of using metallic plates for the closed tops of the box-like structures constituting the inner mold forms, planks or other material may be used. The mold is constructed by fastening the flanges of the metallic plates together and the wall plates of the outer and inner mold forms are held from spreading by suitable means, such as bolts having spacer sleeves thereon which pass through the plates. Lateral displacement of the sides of the mold forms is prevented by rods passing transversely and longitudinally through the mold, which rods are preferably connected to the spacer bolts referred to so that both the interior and exterior mold frames are rigidly held in position from within. Channel irons may also be used which extend across a plurality of plates and are held against the plates by the spacer bolts referred to, which construction will prevent the plates from bulging

and give an added rigidity to the entire structure.

Other features of the invention will be apparent from the detailed description hereinafter to follow, in which a mold designed for casting a concrete dwelling house consisting of a basement and two upper stories having two rooms to a story, will be described in detail. It is not, however, the intention to limit the invention to the specific construction described, but only by the scope of the claims appended hereto.

In the accompanying drawings:

Figure 1 shows a vertical section through a mold for constructing a concrete house in accordance with the principles of the invention, the vertical section being taken on the line 1—1 of Fig. 2;

Fig. 2 is a horizontal section of the mold shown in Fig. 1, taken on the line 2—2;

Fig. 3 is a vertical section on an enlarged scale taken on the line 3—3 of Fig. 1;

Fig. 4 is a section taken on the line 4—4 of Fig. 3;

Fig. 5 is a horizontal section shown in detail, the manner in which the corner pieces of the inner mold forms are supported; and

Fig. 6 is a section taken on the line 6—6 of Fig. 5.

The entire outer mold form and the inner mold form, with the exception of the plates or planks which sustain the concrete floors and roof of the house, are constructed of long narrow metallic mold plates having marginal flanges. The flanges of the plates are provided with uniformly spaced holes which align when the plates are placed in abutting relation during the assembly and clips and wedges which pass through the aligning holes draw the plates together and securely fasten them in place as in Fig. 3.

As shown in Fig. 1, the house consists of a basement A, having side walls *a*, a first story, B, having a floor *b* and side walls *c*, a second story C, having side walls *d* and a floor *e*, and a roof D. Partition walls *f* (see Fig. 2) which divide the space on each story into two separate chambers or rooms, may also be provided.

The walls *a* of the basement and the floor *b* of the first story are cast by mold forms, which are assembled in the following manner. The outer mold form is constructed from plates or panels 10, and the walls of the inner mold form of plates 11. The plates of both forms are vertically disposed and are mounted upon footing course angles 12 which are disposed upon a footing course 13 which is built previously to the assembling of the molds. The plates 10 and 11 are of the same length, as for example, seven feet, and the plates are securely locked together by the clips and wedges passing through their flanges as disclosed in Fig. 3, the clips and wedges being omitted from Fig. 1 for

the sake of clearness. The wall plates 10 of the outer mold are assembled to form a hollow rectangle of a length and width corresponding to the length and width of the house to be formed. At the corners, the plates are secured to angle irons 14 (see Fig. 2) so that when the outer mold is completely assembled, it forms a rigid structure which is self-supporting. The vertical mold plates 11 of the inner mold form are assembled in the same manner, but are joined together at the corners by corner plates similar in construction to a corner plate 15 disclosed in Fig. 5 of the drawing; *i. e.* a plate having two faces at right angles to each other which are provided with flanges 16 to which are clipped the flanges of the abutting plates 11. The side walls of the inner mold form therefore constitute a rigid hollow rectangular frame. However, where the basement is to be divided by a partition wall, instead of having one hollow rectangular form, two such forms are provided, which are spaced from the outer form and from each other, as is clearly indicated by Fig. 2.

Instead of using metallic plates for forming the floors of the building, planks 20 may be used which extend transversely across and rest upon the upper flanges of the plates 11 of the inner mold to close the top face thereof.

To maintain the inner and outer wall plates 10 and 11 in proper spaced relation to each other, bolts or rods 21 pass through suitable openings or apertures in the faces of the wall plates and through holes in channel irons 22 which rest against the flanges of the plates. If desired, the flanges may be notched as at 23 to receive the channel irons. Nuts 24 upon the bolts 21 acting against the channel irons, press the wall plates 10 and 11 against spacer sleeves 25, which may be of concrete and which surround the bolts 21, whereby the wall plates of the inner and outer mold frame are rigidly united together and held in parallelism. These bolts 21 are preferably disposed adjacent the upper and lower ends of the plates, and need not pass through each of the plates which are, as a general rule, about one foot in width; if they are passed through every fourth or fifth plate, it will be sufficient.

To hold the wall plates of the inner and outer molds against lateral displacement, tie-rods 28 are used, which tie-rods are connected to the bolts 21 by means of turn buckles 30. These tie-rods, as will be clear from Fig. 2, extend both longitudinally and transversely of the frame, and since they are rigidly united to the bolts 20, an adequate internal support for both the inner and outer mold frames is provided for holding it against lateral displacement. It may also here be noted that since the channel

irons are also united with the spacer bolts and tie-rods, an added rigidity is given to the entire mold and the plates prevented from bulging.

5 The construction of the outer mold frame for the first story of the building is in general similar to the construction of the outer mold frame for the basement. In Fig. 1 of the drawing, the outer mold 10 plates for forming the exterior mold frame of the first story, have been designated 40, and, as will be clear from this view, they are set directly upon the plates forming the basement, the end flanges of the plates being fastened together by clips and wedges. The plates 40 are of a greater length than the plates 10 for the basement, the additional length being equal to the thickness of the concrete floor plus the thickness of the 20 planks 20.

The inner mold form for the first story of the building differs in construction from the inner mold form for the basement, having, however, the same general characteristic 25 that it consists of a plurality of box-like structures having closed tops and open bottoms. The corner plates 15 at each of the four corners of the two box-like structures shown, are longer than the intermediate vertical plates 46 and extending from one corner plate to another are horizontally disposed plates 47, 48, 49 (see Fig. 1 of the drawing) which plates are clipped to each other at their ends and to the corner plates 30 with their lower edges flush with the bottom of the corner plates. The intermediate wall plates 46 rest upon these horizontal plates 47, 48 and 49, and are clipped thereto in the usual manner. The corner plates 40 15 are each supported upon the planks 20 forming the top of the interior mold of the basement by means of the construction shown in Figs. 5 and 6. U-shaped channel pieces 50 are arranged under each of the 45 corner plates 15, which channel irons have their legs resting upon the planks 20. A bolt 51 passes through the lower flange of the corner plate 15, the channel piece 50, the plank 20, and the top flange of the corner mold plate of the basement mold, whereby when a nut 52 upon the bolt is tightened, the corner plate 15 will be held spaced from the planks 20, and yet rigidly supported upon the corner plate beneath it. The U-shaped spacer 50 is of a height equal to the 50 thickness of the concrete floor which is to be cast. Similar spacers may be placed under the horizontal plates 47 and 48 at their point of jointure, as is shown in Figs. 60 3 and 4, the U-shaped spacer being designated 53 and is shown as resting upon the planks 20, the horizontal plates being held to the intermediate wall plates of the basement mold by means of the bolts 53'. The 65 bolts 51 and 53', if desired, may be sur-

rounded by spacer sleeves 54 so that after the concrete floor is cast, the bolts may be removed. The wall plates of the exterior and interior mold of the first story are held against spreading by spacer bolts 21, similar to the mold forms for the basement story, and these bolts are connected to tie-rods 28 by means of turn buckles 30 as previously described. In this manner, the first story of the building, as well as the basement, is 75 rigidly held in position, and prevented from shifting under the weight of concrete.

Suitable door and window openings are formed by leaving out alining plates in both the exterior and interior molds, and where 80 window openings are to be provided, horizontal plates 60 are utilized to form the window opening of the proper size. In the construction of the interior or inner frame where a door opening is provided, horizontal plates 61 are provided at the upper end, no such plates being necessary at the lower end. However, in the exterior frame whenever a door opening occurs, a special plate 62 should be provided which is of a width 85 equal to the thickness of the planks 20 and the concrete floor of the first story of the building. These horizontal plates 62 will therefore insure that the concrete forming the floor at the point 63 of Fig. 1, will be 90 flush with the remaining floor. The door and window openings are closed by mold plates 63 secured to the flanges of the plates surrounding the opening.

The construction of the third story of the 100 building is similar in all respects to the construction of the second story, with the exception that no door openings are necessary. The roof of the house may be formed by means of planks 65 which extend across 105 and rest upon the flanges of the inner mold forms of the second story. Cornices are formed by planks 66 supported on brackets 67 secured to the wall plate.

It will be seen from this description of 110 the mold, that the outer mold form is a hollow rectangular structure composed of separable units rigidly joined together and of a height to form the entire building. The inner mold, however, is formed of a plurality of different units for each story of the building, each of these units comprising a box-like form having a closed top but an open bottom, which box-like structure is maintained by the tie-rods 28 and bolts 21 115 in spaced relation to the wall plates of the outer frame and to each other to form walls of the building and also the partition walls. It will also be evident that the box-like structures for casting the walls and floors 120 of the first and second story of the building, are superimposed upon the box-like forms which cast the basement of the building and are rigidly supported thereon by means of the spacers 50 and 53, so that between the 125 130

planks of the top of one box-like form and the lower edge of the horizontal plates forming the bottom of the superimposed box-like form, there is a space of, say, six to eight inches which is equal to the thickness of the concrete floor which is to be cast.

After the mold has been completely assembled as described, the concrete is then poured and first fills the spaces between the outer and inner wall plates of the basement to form the side walls and as the space between these wall plates is filled, the level of the concrete rises until it reaches the level above the planks 20 forming the top of an interior mold form. The pouring of the concrete is then continued and some of the concrete will run onto the planks 20 through the space left between the horizontal plates 47, 48 and the planks of the inner mold frames. As the pouring is continued, the level of the concrete rises and fills the space between the wall plates 40 and 41 of the inner and outer molds of the first story of the building. The workman standing upon the planks 20 of the basement floor, then starts to distribute the concrete over the planks 20 until it reaches an even depth, and if sufficient concrete has not entered through the space between the inner mold form during the casting of the walls, more concrete may be distributed either upon the planks 20 direct, or the workman may rake the concrete which is filling the space between the wall plates 40 and 41 of the first story in through the space left above the planks 20 until sufficient concrete is obtained to form a floor for the first story of the building. The pouring of the concrete is continued and the floor for the second story of the building is obtained in the same manner, and after the side walls and floors have been completely cast, the concrete is spread upon the planks 65 and 66 to form the roof and corners of the building. It will be seen that during the pouring operation, since the workman stands directly upon the planks which support the concrete forming the floors of the building, the concrete may be readily worked and distributed until an even depth of the concrete is obtained. This feature of the invention is of extreme importance, since concrete will not readily flow in a horizontal plane and entirely fill the space between two sets of mold plates to provide a floor of uniform thickness. The tie-rod and spacer bolts referred to, are of sufficient strength to sustain the mold plates of the first and second stories in place during the pouring of the concrete, and by using the channel irons described, any bulging of the plates is prevented.

After the concrete has entirely set, the mold is then removed, the spacers 50 and 53, and spacer sleeves 25 being lost in the cast,

but inasmuch as only a small number of 65 these parts are used, they will not detract materially from the finish of the building and will be entirely concealed if an additional finish is used.

In removing the molds, there is no difficulty with the outer mold frame which is taken down commencing with the upper story first, but to relieve the inner molds the footing course angles 12 are first removed, which will permit the wall plates forming 75 the basement of the building to be removed. In removing the inner molds for the first and second stories, the vertical plates 46 are first removed, then the planks 20 and finally the corner plates.

I claim:

1. In a concrete house mold, an outer mold form providing a rectangular frame of a height to form the several stories of a building, an interior mold form consisting of a plurality of box-like structures one at least for each story of the building, said structures having open bottoms and closed tops, and means for supporting the box-like structures one above the other in spaced relation. 90

2. In a concrete house mold, an outer mold form providing a hollow rectangular frame of a height to form the several stories of a building, an interior mold form comprising a plurality of box-like structures having 95 open bottoms and closed tops, the box-like structures for the several stories being superimposed, and means interposed between two superimposed structures for supporting the upper one upon the lower one in spaced relation thereto.

3. In a concrete house mold, an outer mold form of a height to form the several stories of a building, said form being composed of vertically disposed plates and providing a 105 hollow rectangular frame, an inner mold form comprising a plurality of box-like structures having their side walls composed of vertically disposed plates, said structures having open bottoms and closed tops arranged one above the other in spaced relation, and means for supporting said boxes in position.

4. In a concrete house mold, an outer mold form of a height to form the several stories 115 of a building, said form being composed of vertically disposed plates and providing a hollow rectangular frame, an inner mold form comprising a plurality of boxlike structures having their side walls composed of 120 vertically disposed plates, said structures having open bottoms and closed tops arranged one above the other in spaced relation, and means for supporting the upper boxes upon the lower boxes in spaced relation thereto, said means comprising pieces adapted to be lost in the concrete floor when cast.

5. In a concrete house mold, an outer and an inner mold form composed of long relatively narrow vertically disposed wall plates, means passing through some of the 65
5 wall plates of both forms for holding them spaced apart, and means passing transversely and longitudinally through the mold connected to said first named means for preventing the lateral displacement of the
10 forms.
6. In a concrete house mold, an outer and an inner mold form composed of long relatively narrow vertically disposed wall plates, bars passing through some of the plates of 70
15 both forms having means thereon for holding said wall plates spaced apart, and tie rods connected to said bars passing transversely and longitudinally through the interior of said inner form for holding said
20 forms against lateral displacement.
7. In a concrete house mold, an outer and inner mold form composed of long relatively narrow vertically disposed wall plates, bars passing through some of the plates of both 75
25 forms at spaced intervals around the form, said bars having means thereon for holding said plates in spaced relation, and adjustable tie rods passing transversely and longitudinally through the interior of said inner mold
30 form for holding said forms against lateral displacement.
8. In a concrete house mold, an outer and an inner mold form, said outer mold form comprising a rectangular frame of a height 80
35 to form the several stories of a building and composed of vertically disposed plates, said inner mold form being composed of a plurality of superimposed box-like structures, means for supporting said box-like structures one above the other in spaced relation, and internal supporting means for holding said inner and outer forms against lateral displacement.
9. In a concrete house mold, an outer mold 85
45 form comprising a hollow rectangular frame of a height to cast several stories of a building, an inner mold form composed of box-like structures having closed tops and open bottoms, one at least for each story of the
50 building, said structures being arranged one above the other in spaced relation, and internal supporting means passing through said mold forms for holding them against lateral displacement.
10. In a concrete house mold, an outer mold form comprising a rectangular frame of a height to form the several stories of a 90
55 building, said form being composed of long relatively narrow vertically-disposed plates, horizontal bars surrounding said outer mold form, and means for clamping said bars together in the form of a rectangular supporting frame for said outer mold form.
11. In a concrete house mold, an outer 95
60 mold form comprising a rectangular frame of a height to form the several stories of a building, said form being composed of long relatively narrow vertically-disposed units, horizontal bars disposed around said outer mold form providing a series of horizontal supporting rectangular frames, and tie-rods connecting the bars of said frames together.
12. In a concrete house mold form, an outer mold form of a height to form the several stories of a building, said form being composed of long relatively narrow vertically-disposed units, horizontal bars disposed around said outer mold form, and means for clamping said bars together providing a series of spaced rectangular supporting frames 100
65 for said outer mold form.
13. In a concrete house mold form, an outer mold form, an inner mold form, each being composed of long relatively narrow vertically-disposed units, horizontal bars 70
75 disposed exteriorly of said outer form and clamped against the side walls thereof, and horizontal bars disposed interiorly of said inner form and clamped against the side walls thereof.
14. In a concrete house mold form, an outer mold form of a height to form the several stories of a building comprising a rectangular frame composed of long relatively narrow vertically-disposed units, an inner mold form comprising a plurality of box-like structures having closed tops and open bottoms disposed one above the other in spaced relation, said box-like structures having their side walls composed of long relatively narrow vertically-disposed units, and internal supporting means for supporting said box-like structures in spaced relation and for preventing lateral displacement of said inner and outer forms.
15. In a concrete house mold form, an outer mold form of a height to form the several stories of a building comprising a rectangular frame composed of long relatively narrow vertically-disposed units, an inner mold form comprising a plurality of box-like structures having closed tops and open bottoms disposed one above the other in spaced relation, said box-like structures having their side walls composed of long relatively narrow vertically-disposed units, and means including horizontal bars providing rectangular frames surrounding the outer mold form and disposed within said box-like structures for preventing lateral displacement of said forms.
16. In a concrete house mold form, an outer mold form of a height to form the several stories of a building comprising a rectangular frame composed of long relatively narrow vertically-disposed units, an inner mold form comprising a plurality of box-like structures having closed tops and

open bottoms disposed one above the other in spaced relation, said box-like structures having their side walls composed of long relatively narrow vertically-disposed units, 5 horizontal bars providing rectangular frames surrounding said outer mold form and disposed within said box-like structures, and rods passing transversely and longitudinally of said form connecting said bars together

for preventing lateral displacement of said forms.

In witness whereof, I subscribe my signature, in the presence of two witnesses.

ROBERT A. BACHMAN.
